UNITED STATES PATENT OFFICE.

HENRY HERBERT YELF, OF SOUTHSEA, ENGLAND.

INSTRUCTIONAL DUMMY PRACTICE-KEYBOARD APPARATUS.

Application filed March 13, 1923. Serial No. 624,821.

To all whom it may concern:

Be it known that I, HENRY HERBERT YELF, a subject of the King of Great Britain and Ireland, and a resident of Southsea, Hampshire, England, have invented a certain new and useful Instructional Dummy Practice-Keyboard Apparatus, of which the following is a specification.

My invention relates to improvements in instructional dummy practice keyboards as applied to typewriters, adding and calculating machines, printers' composing machines, and the like, and has for its object to provide a cheap, novel and simple means of reproducing approximately the action and tension of, for instance, an average standard typewriter keyboard for practice and instructional purposes.

My invention relates more particularly to the type of apparatus wherein a single dummy keyboard bearing characters is resiliently mounted in a frame so as to be capable of depression by pressure at any of the points where characters are marked.

The present invention consists broadly of the employment of a single keyboard, containing characters, which keyboard is not connected to the supporting frame but supported merely by a central compression spring disposed thereunder, whereby when depressed at any point away from the centre a combined action of spring-yield and leverage is obtained. Further, by this means, the floating keyboard may be easily detachable for the purpose of interchanging the pattern at will, thus allowing for any range of difference in keyboard styles, and the keyboard proper so mounted in its frame can be disposed in an outer combination box and copyholder, all as will be more fully described hereinafter with reference to the accompanying drawings, wherein:—

Figure 1 is a front elevation of one embodiment of the complete apparatus adapted for use in its application to a typewriter.

Figure 2 is a transverse section thereof on the line 2—2, Figure 1.

Figure 3 is a perspective view of the keyboard component and its framework removed from the box, the keyboard being partly broken away for clearness; and

Figure 4 is an enlarged section on the line 4—4, Figure 1, keyboard removed.

Referring to the embodiment illustrated by way of example in the accompanying drawings, *a* is a floating keyboard sup-

ported on the frame base *b* by means of a compression spring *c* resting in a shallow depression *d* in the base. The frame, keyboard and containing box or casing (to be described) may be constructed of wood, metal or any other suitable material. The base *b* is rectangular, in the form shown, and has side pieces, *e*, *e*, against the faces of which the side edges of the keyboard rest, and inwardly projecting ribs, *f*, *f*, or their equivalents such as stops, are provided to limit upward movement of the keyboard *a*. Corner flanges *g*, *g*, are secured to the front ends of the sides *e*, *e*, to retain the keyboard in position.

The keyboard *a* may be a flat plate like member as shown arranged in inclined fashion, and is furnished with an assembly of characters inscribed thereon, applied thereto, or fixedly formed in the nature of buttons or equivalents *h* representative of the keys of a typewriter as for the example given. The keyboard *a* may be stepped or terraced, or the buttons themselves arranged in a series of progressive steps. The strip *i* is equivalent to the usual typewriter space-bar.

In operation, it will be seen that the keyboard is depressible at any spot, and as the centre spring *c* acts as a fulcrum in every case of pressure at points displaced from the axial line of the spring, a combined leverage and spring-yield is the resultant action.

A separate dummy shift-key *j* is independently mounted in a side piece *e*, and this is arranged to be resiliently depressed against the action of a leaf spring or the like *k* housed in a recess *l*—see particularly Figure 4.

The practice apparatus so far described is carried in a box-like member *m* provided with a lid *n* and drop front *o*. The lid *n* is furnished with supporting leg or flap *p* to maintain it in an inclined or upright position as shown in Figures 1 and 2, the leg or flap *p* having a flexible or hinged connection *q* to the lid *n*. The interior of the lid *n* is constructed as a copy-holder, such for instance by means of the clips *r* whereby a pack of instruction cards or other copy can be supported in front of the operator.

I claim:

1. A practice keyboard device including a casing, a keyboard having key characters thereon arranged in said casing, and a compression spring located beneath said key-

board and constituting the support therefor to produce the effect of key tension.

2. A practice keyboard device including a casing, a keyboard plate loosely positioned in said casing and having key characters thereon, and a single centrally located compression spring arranged between the casing and the underside of the keyboard plate.

3. A practice keyboard device including 10 a casing, a keyboard plate loosely positioned in said casing and having key characters thereon, a single centrally located compression spring arranged between the casing and the underside of the keyboard plate, and a 15 spring supported shift key arranged in the casing at one side of the keyboard plate.

4. A practice keyboard device including a casing having inclined abutment members, a keyboard plate having thereon key characters,

and a compression spring arranged to normally maintain said keyboard plate against the inclined abutment members of the casing..

5. A practice keyboard device including a box-like casing provided with a hinged lid, 25 a frame arranged within the casing and including side pieces, abutment ribs carried by the side pieces, a central compression spring arranged within said frame, a keyboard plate resting on said spring and held 30 by the same against the inner faces of said ribs, and corner flanges secured to the front ends of the side pieces.

In testimony whereof I have affixed my signature hereto this first day of March, 35 1923.

HENRY HERBERT YELF.
